UNITED STATES PATENT OFFICE

2,058,779

TEXTILE MATERIAL

Henry Dreyfus, London, and William Alexander Dickie, Spondon, near Derby, England, assignors to Celanese Corporation of America, a corporation of Delaware

No Drawing. Original application December 10, 1930, Serial No. 501,461. Divided and this application July 18, 1934, Serial No. 735,790. In Great Britain December 24, 1929

7 Claims. (Cl. 28—1)

This invention is a division of United States application Serial No. 501,461 filed 10th December, 1930 and relates to the manufacture of textile fabrics, more particularly textile fabrics exhibiting crepe effects.

Textile materials exhibiting crepe effects have long been obtained by employing in their construction highly twisted yarns (hereinafter referred to as crepe yarns or crepe threads) made of natural silk in the gummed state, the crepe effects appearing when the gum is subsequently removed by a suitable scouring or like treatment. Crepe effects are, however, only obtained with difficulty by employment of highly twisted crepe threads made of cellulose acetate or other organic derivatives of cellulose. Thus, for instance, a fabric containing highly twisted weft threads of cellulose acetate shows only a relatively slight crepe effect after treatment in an aqueous scouring bath.

We have now discovered a new method for the production of crepe fabrics and more particularly crepe fabrics containing cellulose acetate or other cellulose esters or ethers. According to our invention, fabrics exhibiting crepe effects are produced by subjecting to the action of an aqueous medium fabrics made with crepe twisted threads, particularly crepe twisted threads of cellulose acetate or other cellulose ester or ether, which threads are impregnated with a zinc halide, e. g. zinc chloride, or calcium chloride or nitrate or sodium iodide. It will be noted that each of these compounds has a high affinity for water.

In carrying the invention into effect, the impregnation of the filaments or fibres of the crepe twisted threads may be effected in any desired manner, for example the compound having a high affinity for water may be applied to fabrics containing the crepe twisted threads. The compounds may, however, be incorporated in the materials at any other convenient stage of the manufacture of the fabrics or of the manufacture of the crepe threads, or of the yarns or filaments from which they are produced. For example the compounds may be applied to or incorporated in the crepe threads prior to weaving and either before or after the application of the requisite high degree of twist. For example the threads may, prior to crepe twisting, be treated with an aqueous solution of one of the compounds and then dried.

Where the crepe threads are made of or contain artificial filaments or fibres, the said compounds may be incorporated in the artificial filaments or fibres during processes of their manu-

facture. For example, they may be incorporated in solutions of cellulose esters or ethers and the latter converted into filaments by extrusion into an evaporative atmosphere or into a coagulating bath as may be desired or requisite. Thus, calcium chloride or nitrate or sodium iodide may be incorporated in cellulose acetate spinning solutions. In this manner there may be produced filaments which, after forming into highly twisted crepe threads, yield fabrics which may readily be caused to exhibit crepe effects by simple treatment with an aqueous liquid.

Fabrics containing crepe twisted threads or filaments or fibres impregnated with the compounds of the invention may be treated with water or other aqueous liquid in any desired manner in order to effect creping, i. e. the production of the desired effects. A creping treatment with water may, for example, be effected at ordinary or raised temperature and with the addition or not of soaps, wetting agents, salts, acids or any other substances designed to accentuate or otherwise modify the creping action of the water. If desired the creping treatment may be combined with another subsequent treatment, for example with the dyeing of the fabric.

If desired the crepe threads may be sized at any suitable stage, e. g. before or after twisting to the requisite high degree. Preferably such sizing and the aqueous after-treatment are effected in accordance with the principles described in United States application Serial No. 491,070 filed 24th October, 1934.

The invention is particularly applicable to the production of crepe fabrics comprising crepe threads made of or containing filaments of organic derivatives of cellulose, for example cellulose esters, e. g. cellulose acetate, formate, propionate or butyrate, or cellulose ethers, e. g. methyl, ethyl or benzyl cellulose. For instance crepe threads may be employed which consist entirely of filaments of cellulose esters or ethers or which comprise also other textile fibres or filaments, for example fibres or filaments of cotton, silk or regenerated cellulose. Again, fabrics may be constructed entirely of yarns of organic substitution derivatives of cellulose or they may comprise threads or yarns of other textile materials, for example cotton, silk or a regenerated cellulose type of artificial silk.

The degree of twist imparted to the yarns or threads serving to give the crepe effects may be similar to that commonly employed in the production of crepe threads from silk in the gummed state, but any other suitable degree of crepe twist

may be employed according to the effects it is desired to produce. The crepe threads may be sized in any desired or suitable manner and at any suitable stage, for example prior to twisting.

5. The highly twisted crepe threads may be incorporated in the fabrics in any suitable manner; for example the weft alone may be wholly or partially composed of such threads, or the warp may also contain them. In general it is found convenient 10 to employ threads of relatively low twist in the warp and to employ as the weft both crepe threads having a left-hand crepe twist and crepe threads having a right-hand crepe twist. The threads having right- and left-hand crepe twist respectively may be incorporated in any convenient manner, for example pairs of weft threads of right-hand crepe twist may alternate with pairs of threads of left-hand crepe twist. If desired composite crepe threads may be prepared by 20 doubling the impregnated or treated crepe threads with crepe threads not so treated. By weaving such threads into fabrics, with or without other threads whether of crepe twist or of low twist, and subsequently subjecting the material of the 25 treated threads to an aqueous treatment, fabrics exhibiting a variety of fancy and other effects may be produced.

What we claim and desire to secure by Letters Patent is:—

30. 1. Process for producing crepe fabrics, which comprises treating with an aqueous liquid a fabric containing crepe twisted threads of an organic derivative of cellulose, which threads are substantially dry and are impregnated with an agent having a high affinity for water.
2. Process for producing crepe fabrics, which comprises treating with an aqueous liquid a fabric containing crepe twisted cellulose acetate threads

which are substantially dry and are impregnated with an agent having a high affinity for water.

3. Process for producing crepe fabrics, which comprises treating with an aqueous liquid a fabric containing crepe twisted threads of an organic derivative of cellulose, which threads are substantially dry and are impregnated with an inorganic salt having a high affinity for water. 5

4. Process for producing crepe fabrics, which comprises treating with an aqueous liquid a fabric containing crepe twisted cellulose acetate threads which threads are substantially dry and are impregnated with an inorganic salt having a high affinity for water. 10

5. Process for producing fabrics exhibiting crepe effects which comprises crepe twisting threads spun from a solution of an organic derivative of cellulose, said solution containing a substance having a high affinity for water, incorporating the crepe twisted threads in a fabric, and 15 subjecting the fabric to the action of an aqueous medium. 20

6. Process for producing fabrics exhibiting crepe effects, which comprises crepe twisting threads spun from a solution of cellulose acetate, 25 said solution containing a substance having a high affinity for water, incorporating the crepe twisted threads in a fabric, and subjecting the fabric to the action of an aqueous medium.

7. A process for producing crepe effects on fabrics which comprises fabricating highly twisted cellulose acetate yarns containing a substance which has a high solution tension for water into a fabric, and treating the fabric with an aqueous medium. 30
